UNITED STATES PATENT OFFICE.

CALVIN B. PATCH, OF GLENELLYN, ILLINOIS, ASSIGNOR TO WILLIAM H. MINER, OF CHAZY, NEW YORK.

ROCKER SIDE BEARING.

1,250,638.

Specification of Letters Patent. Patented Dec. 18, 1917.

Application filed July 14, 1916. Serial No. 109,235.

To all whom it may concern:

Be it known that I, CALVIN B. PATCH, a citizen of the United States, residing at Glenellyn, in the county of DuPage and 5 State of Illinois, have invented a certain new and useful Improvement in Rocker Side Bearings, of which the following is a full, clear, concise, and exact description, reference being had to the accompanying 10 drawings, forming a part of this specification.

This invention relates to improvements in rocker side bearings.

The object of the invention is to provide 15 a simple and relatively cheap rocker side bearing for railway cars, having novel spring means for returning the rocker to normal position after each actuation.

In the drawing forming a part of this 20 specification, Figure 1 is an end elevation of portions of a truck and body bolster of a car, showing my improvements in connection therewith. Fig. 2 is an enlarged, longitudinal section of the side bearing proper 25 and taken substantially on the line 2—2 of Fig. 1. Fig. 3 is a transverse, vertical sectional view taken on the line 3—3 of Fig. 2. And Fig. 4 is a horizontal, sectional view taken on a plane passing through the 30 axis of oscillation of the rocker and showing a different embodiment of my invention.

Referring now to Figs. 1, 2 and 3, 10 denotes a car body bolster and 11 a truck bolster pivotally connected thereto in the usual 35 manner. The body bolster 10 is provided on its under-face with a striking plate 12 and the truck bolster has secured thereto on its upper face, the improved rocker bearing designated generally by the reference A.

40 The bearing A, as shown, comprises a base plate or casting 13 having extended bottom flanges 14—14 by which it is riveted or otherwise secured to the bolster. The base casting 13 is also provided with spaced side 45 walls 15—15 and a central raised section 16 having a curved bearing 17 formed in its upper face to receive the cylindrical lower end 18 of the rocker 19, the latter having an enlarged cylindrical bearing surface 20 50 adapted to coöperate with the striking plate 12. The rocker 19 is provided with a transversely extending perforation 21, being in alinement with corresponding perforations or openings 22—22 in the side walls of the 55 base casting when the rocker is in position.

Extending through the portion 18 of the rocker and at right angles to the axis of oscillation of the rocker is a fixed pin or rivet 23, located at the center of the recess 21. Secured at their inner ends to the pin 60 23 are springs 24—24, the latter having their outer ends extended into the recesses 22—22 and secured to cotters 25—25. The springs 24 are so secured at their ends as to prevent rotation with respect to the cotters 65 25 and the fixed pin 23.

When the rocker is operated so as to swing to one side or the other of normal position, it is apparent that the springs 24—24 will be twisted, one in the direction of the twist 70 of the coil and the other in the opposite direction. Consequently, when pressure on the rocker is removed, the stored energy due to the twisting of the coils will automatically operate to return the rocker to normal 75 position. It is apparent that both the rocker and the base member may be made in the form of castings and hence, cheaply manufactured, without the necessity for machining of the parts. Furthermore, changes or 80 repairs may be easily made since the parts are readily accessible.

In the construction illustrated in Fig. 4, the base member or casting 113 is provided with side walls 115 and 116, the former 85 having an integral boss 117 slotted to receive the end of a leaf spring 124 which is held in position by means of a cotter 125. The rocker has the lower cylinder section thereof provided with a recess 121 which is flared 90 toward the side wall 115 and within which is received the inner end of the leaf spring 124 and upon release of the pressure on the rocker, the stored up energy in the twisted spring will automatically return the rocker 95 to central position.

I claim:

1. In a side bearing, the combination with a base casting, of a rocker mounted thereon, and a spring for returning the rocker to 100 normal, said spring extending parallel to the axis of the rocker from the interior thereof to the base casting and being non-rotatably secured at its ends to both.

2. In a side bearing, the combination with 105 a base casting, of a rocker mounted thereon and having an opening in alinement with its axis of oscillation, and a spring member extending from the base casting to the interior of said opening and adapted to automatically 110

cally return the rocker to normal position after actuation.

3. In a side bearing, the combination with a base casting, of a rocker mounted thereon and having an opening in alinement with its axis of oscillation, and a spring member extending from the base casting to the interior of said opening and adapted to automatically return the rocker to normal position after actuation, said spring being non-rotatably secured at its ends to the rocker and the base casting.

4. In a side bearing, the combination with a base casting having upstanding spaced side walls with a bearing therebetween, of a rocker having a cylindrical lower portion coöperating with said bearing, the rocker

having an opening extending therethrough in alinement with the axis of said cylindrical portion, the said side walls being also provided with openings in alinement with the opening in the rocker, and springs connected at their centers to the rocker within said opening therein, said springs being extended at their ends into said openings in the side wall and non-rotatably secured to the side walls.

In witness that I claim the foregoing I have hereunto subscribed my name this 12th day of July 1916.

CALVIN B. PATCH.
